ENGINE STARTER

John W. Fitz Gerald, Milwaukee, Wis., assignor
to Briggs & Stratton Corporation, Milwaukee,
Wis., a corporation of Delaware

Application May 15, 1937, Serial No. 142,787

7 Claims. (Cl. 74—7)

This invention relates to improvements in engine starters and refers particularly to starters for automobile engines.

Heretofore, many different types of starters have been proposed, but in general they all embodied some form of screw which, upon initial operation of the starter device, effected engagement between the starter pinion and the ring gear of the engine. With this generally accepted design, there was always the possibility of the pinion engaging the ring gear with the teeth meeting end to end, and at all times the shock incidental to picking up the load of the engine had to be contended with.

15 To meet these contingencies, good design required both endwise and torsional yieldability. In starters now generally in use, this yieldability, if provided, was obtained through the use of a spring or springs, and while this construction afforded the desired yieldability, the possibilities of breakage and its comparative noisiness were objectionable.

With these and other objections to past and existing types of engine starters in mind, this invention has as one of its objects to provide an improved construction for engine starters which entirely obviates the use of springs and at the same time has all of the required resiliency.

Another object of this invention is to provide 30 an engine starter which is considerably more quiet in operation than those heretofore in use.

More specifically it is an object of this invention to provide an engine starter so constructed that a rubber cushion may be employed in place of the 35 spring or springs heretofore used.

Another object of this invention is to so construct an engine starter of the character described that the rubber cushion is placed in compression in the same direction to afford both endwise and 40 torsional resiliency.

A further object of this invention is to provide an engine starter of simpler and less expensive design and construction.

With the above and other objects in view which 45 will appear as the description proceeds, this invention resides in the novel construction, combination and arrangement of parts substantially as hereinafter described and more particularly defined by the appended claims, it being understood 50 that such changes in the precise embodiment of the herein disclosed invention may be made as come within the scope of the claims.

The accompanying drawings illustrate one complete example of the physical embodiment of the 55 invention constructed in accordance with the best

mode so far devised for the practical application of the principles thereof, and in which:

Figure 1 is a view partly in side elevation and partly in longitudinal section, of an engine starter constructed in accordance with this invention; 5

Figure 2 is a view similar to Figure 1, but showing the manner in which endwise yieldability is obtained;

Figure 3 is a view similar to Figure 1, illustrating the manner in which torsional yieldability is 10 obtained;

Figure 4 is a perspective view of the nut member;

Figure 5 is a perspective view of the stop member or abutment which cooperates with the nut 15 member;

Figure 6 is a perspective view of the rubber cushion which is interposed between the nut member and the abutment; and

Figure 7 is a cross sectional view taken through 20 Figure 1 on the plane of the line 7—7.

Referring now particularly to the accompanying drawings in which like numerals indicate like parts throughout the several views, the numeral 5 designates the ring gear of an engine to be 25 started, and the numeral 6 represents the starting motor. The motor 6 has its shaft 7 extended past the ring gear to mount a pinion 8 which is automatically moved into mesh with the ring gear upon initial operation of the starting motor 30 and disengaged therefrom when the engine starts.

The pinion 8 is freely rotatably and slidably mounted on the shaft 7, and has a sleeve 9 extending longitudinally therefrom. The outer end of the sleeve 9 is provided with threads 10 which 35 engage the threads 11 of a nut member 12.

The nut member 12 has an annular flange 13 and two diametrically opposed driving lugs 14 on its outer end. These lugs 14 are of a size to be slidably received in the spaces between two 40 driving lugs 15 formed on a collar-like abutment or stop member 16. This member 16 has a flange 17 similar to the flange 13 of the nut member, and is rigidly secured to the outer end of the shaft in any suitable manner, as by a set screw 18. 45

The interengaging lugs 14 and 15 provide a non-rotatable but freely slidable driving connection between the nut member and the stop or abutment 16, and inasmuch as the stop member or abutment is fixed to the shaft, a driving connection is established between the shaft and the nut member. 50

Confined between the flanges 13 and 17 of the nut member and the abutment, respectively, is a 55 ring-like rubber cushion 19, its bore 20 being of a

size to fit the interengaged lugs 14 and 15. The normal thickness of the cushion ring 19 is such that when the starter device is inoperative, as shown in Figure 1, and the pinion is retracted, the

5 shown in Figure 1, and the pinion is retracted, the
nut member and the collar-like stop member or
abutment are longitudinally spaced apart a sub-
stantial distance, this distance being limited by a
cover 21 which encircles the cushion member and
10 has inwardly directed flanges 22 on its opposite
ends to engage over the marginal edges of the
flanges 13 and 17.

15 Mounted on the shaft 7, preferably in line with the inner face of the ring gear 5, is a stop 23 against which the pinion 8 abuts when fully meshed with the ring gear. The stop 23 is fixed to the shaft in any suitable manner, as by means of a set screw 24.

Operation

20 With the parts in their positions illustrated in Figure 1 at which time the cushion ring 19 is entirely free and expanded, initial rotation of the shaft 7 by the starting motor causes the pinion 8 to move forwardly toward the ring gear 5, this action being produced in the conventional manner by the inertia of the pinion acting in conjunction with the threaded connection between the screw 10 and the threads of the nut member.

30 If the pinion should strike the ring gear end to end, as depicted in Figure 2, the forward advance of the pinion is arrested, but without shock or strain to the parts, for as shown in Figure 2, such interruption of the forward endwise motion of the pinion merely compresses the rubber cushion ring slightly. This is so by reason of the fact that when the endwise motion of the pinion is arrested, the continued relative rotation of the nut member with respect to the screw 35 causes the nut member to "climb out" onto the threads of the screw toward the stop member or abutment 16, thus compressing the cushion ring.

36 This action is

This condition, however, is but momentary as it requires merely a slight rotation of the pinion to mesh the same properly with the ring gear, whereupon the forward advance of the pinion continues until it strikes the stop member 22.

Upon the engagement of the pinion with the stop 23, the same compression of the rubber cushion ring as heretofore described takes place to provide torsional resiliency. In this instance, the load of the engine holds the pinion against rotation and as its endwise movement is prevented by the stop 23, the nut member is caused to "climb out" on the threads of the screw to compress the cushion ring. The compression of the ring continues until the potential energy being stored up in the cushion ring equals the break-away load of the engine, whereupon this stored energy is released to aid the starting motor in initially turning over the engine.

Upon starting of the engine, the overrunning ring gear causes the screw to withdraw the pinion from the ring gear in the same manner as in

65 From the foregoing description taken in connection with the

connection with the accompanying drawings, it will be readily apparent.

be readily apparent to those skilled in the art, that this invention provides an engine starter of simple design and construction wherein the desired endwise and torsional yieldability is obtained in a manner which entirely obviates the use of springs with its attendant possibility of breakages, and insures a quieter and smoother operating device.

75 What I claim as my invention is:

1. In an engine starter of the character described: a motor driven shaft; a pinion mounted on the shaft; means for causing endwise motion of the pinion on the shaft upon relative rotation of the pinion and shaft, including two members having slidably but non-rotatably engaged parts which move endwise with respect to each other whenever endwise movement of the pinion is restrained and relative rotation between it and the shaft continues; and a cushion ring encircling said parts and yieldingly opposing endwise movement of said members toward each other. 5 10

2. In an engine starter of the character described: a motor driven shaft; a pinion slidable and rotatable on the shaft; means for causing the pinion to move endwise along the shaft including a member having a threaded connection with the pinion; another member fixed with respect to the shaft, said members having slidably but non-rotatably engaged parts; and a cushioning ring encircling said parts for yieldingly opposing endwise movement of said members toward each other. 15 20

3. In an engine starter of the character described: a shaft; a member fixed to the shaft; a screw freely rotatable and slidable on the shaft; a nut member threaded on the screw, said nut member and said shaft carried member having slidably but non-rotatably engaged parts; and a cushioning ring encircling said parts and confined between said members. 25 30

4. In an engine starter of the character described: a motor driven shaft; a pinion freely slideable and rotatable on the shaft; a sleeve; a threaded connection between the pinion and sleeve adapted upon relative rotation between the pinion and sleeve to impart endwise motion from one of said elements to the other; another sleeve fixed to the shaft, said sleeves having slidably but non-rotatably engaged parts providing a driving connection; and a rubber cushion ring encircling said parts and confined between the sleeves to yieldingly oppose endwise movement thereof toward each other. 35 40

5. In an engine starter of the character described: a motor driven shaft; a pinion freely slidable and rotatable on the shaft; a sleeve; a threaded connection between the pinion and sleeve adapted upon relative rotation between the pinion and sleeve to impart endwise motion from one of said elements to the other; another sleeve fixed to the shaft, said sleeves having slidably but non-rotatably engaged parts which together form a cylinder and provide a driving connection between the sleeves while allowing relative endwise motion therebetween; a rubber cushion ring encircling and fitted on the cylinder formed by said parts and confined between the sleeves to yieldingly oppose endwise movement thereof toward each other; and a cover engaged over the sleeves and the cushion ring therebetween and having means engageable with the sleeves to limit their movement apart. 6. In an engine 45 50 55 60

6. In an engine starter of the character described: a shaft; a pinion freely slideable and rotatable on the shaft and having a sleeve extended therefrom; an external thread on the sleeve; a nut member having threaded engagement with the threads of the sleeve; a collar fixed to the shaft; the nut member and collar having slidably but non-rotatably engaged parts; means for limiting relative movement apart of said nut member and collar; and compressible means interposed between the nut member and collar and 65 70 75

2,136,046

encircling their interengaged parts for yieldingly opposing endwise movement of the nut member and collar toward each other.

7. In an engine starter of the character described: a motor driven shaft; a pinion freely 5
slidable and rotatable on the shaft and having an externally threaded portion; a nut member having threaded engagement with said portion of the pinion; an annular flange on the nut member; a collar fixed to the shaft; an annular flange 10

on the collar similar to that of the nut member; slidably but non-rotatably engaged parts carried by the nut member and collar between their flanges to provide a sliding driving connection between the shaft and nut member; and a rubber ring encircling said parts and confined between the flanges for yieldingly opposing endwise movement of the nut member toward the collar. 5
